ALFRED LAWTON, OF PHILADELPHIA, PENNSYLVANIA, ASSIGNOR
TO FRANCIS N. LAWTON, OF SAME PLACE.

Letters Patent No. 92,461, dated July 13, 1869.

IMPROVED APPARATUS FOR RAISING COAL.

The Schedule referred to in these Letters Patent and making part of the same.

To all whom it may concern:

Be it known that I, ALFRED LAWTON, of Philadelphia, Pennsylvania, have invented an Improvement in Raising Coal and other granular material; and I do hereby declare the following to be a full, clear, and exact description of the same.

My invention consists in raising coal and other granular material, by means of a bucket or other suitable vessel, arranged to slide in a shaft, or its equivalent, which extends so far below the ground or platform on which is deposited the coal or other material to be raised, that the latter will of itself pass into the bucket, all substantially as described hereafter.

The object of my invention is to save the tedious and costly labor demanded in the removal of coal, &c., by the aid of shovels and wheelbarrows.

In order to enable others to practise my invention, I will now proceed to describe its construction and operation, reference being had to the accompanying drawing, which forms a part of this specification, and in which—

Figures 1 and 2 are vertical sections of apparatus which may be used in carrying out my invention, and

Figure 3, a plan view of the same.

A represents the surface of the ground or platform, on which the coal is deposited, and

B is a shaft, built of wood, iron, or other suitable material, to such a height above the ground as circumstances may demand, the shaft being continued below the surface of the ground or platform, as shown in the drawing.

In the present instance, the shaft is of the oblong sectional form illustrated in fig. 3; and in the front side b, of the shaft, there is an opening, e, the lower edge of which is continued, in the form of an inclined plane, f, to the surface of the ground or platform. It is not essential, however, that there should be but one of these openings and inclined planes, as they may be also arranged at the back, or, if desired, upon all four sides of the shaft.

On the inside of the shaft a sliding door, h, is so arranged that it can be made to close or uncover the opening e, the door occupying a position close to the inside of the front wall b, and being operated, in the present instance, by a rod, l, extending upward to or above the top of the shaft; but the said door may, in some instances, be operated from below the shaft, without departing from my invention.

A bucket, D, conforming in shape to, but somewhat less, as regards length and breadth, than the interior of the shaft, is arranged to slide in guides in the latter, the bucket being suspended by a rope or chain, y, and being raised and lowered by any suitable system of gearing, under the control of an attendant.

In using the above-described apparatus, the bucket is first lowered to the bottom of the shaft, as shown in fig. 1; the door h is then elevated, so as to uncover the whole or part of the opening e, when coal from the mass upon the ground or platform A, and surrounding the shaft, will rush down the inclined plane f, and into the bucket D.

When the bucket is full, the attendant depresses the door h, thereby closing the opening e, and preventing the further passage of coal through the same. He then, by a proper system of signals, communicates with a second attendant, who so manipulates the gearing that it shall raise the bucket to the top of the shaft, where the latter may be tilted, or its contents otherwise disposed of in any desired manner.

The importance of my invention as a labor-saving apparatus will be understood, if we suppose it to be erected at any place where large masses of coal are stored, to be removed from time to time, for instance, at the coal-depot of a railroad or canal, where it has been the practice to remove the coal from heaps there deposited by wheelbarrows and shovels, demanding the services of a number of laborers, who conveyed the coal in the wheelbarrows up inclined planes, and tilted them into cars or other vehicles, or into chutes communicating therewith. All this tedious and costly labor may be dispensed with by the erection of the above-described simple apparatus, as the coal will of itself fall into the bucket, and the latter may be raised to any desired height, and its contents tilted into a chute, or directly into a car or other suitable receptacle.

The apparatus may be used to advantage in many other localities, as, for instance, at coal-mines, or where vessels have to be loaded with coal. And in unloading vessels, the apparatus may be erected upon the same, the shaft taking the form of an enclosed hatchway. The apparatus may also be employed for raising grain or other granular material.

In some instances, where it is not desirable that the coal should be filled entirely around the apparatus, as illustrated in the first two figures of the drawing, and where there is but one opening e and inclined plane f, it may be of advantage to provide walls, x x, shown by dotted lines, fig. 3, for the purpose of confining the coal to one side of the shaft only. In this case, it is not essential that the entire shaft should be an enclosed structure. All that portion above the ground or platform, with the exception of the front b, against which the mass of coal bears, may consist of a skeleton frame, sufficiently substantial to guide the bucket and to support the necessary hoisting-gear and other appliances.

Where the coal surrounds the apparatus, however, it is essential that the shaft should be entirely closed to a height at least greater than that of the mass.

When the shaft, instead of being permanently fixed to the ground, is secured to and arranged to project below the surface of a platform, the latter can be mounted upon wheels, and can be provided with a suitable turn-table, so that the apparatus may be moved to any desired position, and caused to face in any direction. The shaft can, also, without departing from my invention, be so inclined that a car operated by the hoisting-gear, and running upon one side of the said shaft, may be substituted for the suspended bucket.

It will be seen, that the main feature of my invention is the sinking of the shaft so far below the surface of the ground or platform, that the coal will of itself pass into the bucket or hoisting-vessel D. It is by this simple contrivance that the removal of coal is facilitated, and the labor heretofore expended in that operation saved.

I claim as my invention, and desire to secure by Letters Patent—

1. The raising of coal or other granular material by means of a bucket or other suitable vessel, arranged to slide in a shaft, or its equivalent, which extends so far below the ground or platform on which is deposited a mass of the coal or other material to be raised, that the latter will of itself pass into the bucket, all substantially as set forth.

2. In combination with the said shaft, or its equivalent, the opening e in the same, the inclined plane f, and movable door h, arranged, in respect to the ground or platform on which the coal is deposited, substantially as and for the purpose specified.

In testimony whereof, I have signed my name to this specification, in the presence of two subscribing witnesses.

ALFRED LAWTON.
